UNITED STATES PATENT OFFICE.

JACOB B. BAILEY, OF NEW YORK, N. Y.

IMPROVED CURTAIN-FIXTURE.

Specification forming part of Letters Patent No. 55,454, dated June 12, 1866.

To all whom it may concern:

Be it known that I, JACOB B. BAILEY, of the city and State of New York, have invented, made, and applied to use a certain new and useful Improvement in Curtain-Fixtures; and I do hereby declare the following to be a full, clear, and exact description of the said invention, reference being had to the annexed drawings, making part of this specification, wherein—

Figure 1 is a section longitudinally of the curtain-roller, showing the two ends of said roller. Fig. 2 is an end view of the wooden roller. Fig. 3 shows the bracket at the cord end of the roller, and Fig. 4 is a side view of the cord-roller.

Similar marks of reference denote the same parts.

Spools have heretofore been made for the rollers of window-curtains in which the spool is held to place at the end of the roller by spurs projecting inward and by the pin forming the axis, or by nails, as usual. In this case the spool did not have a groove adapted to the reception of an endless cord, and there was not an opening through it for the reception of the roller.

The nature of my said invention consists in a ring-shaped cord-pulley having a grooved periphery for the reception of the endless cord, and teeth within the ring that penetrate the surface of the wooden roller that passes through said ring into a semicircular shoe forming the bracket, and I obtain friction to prevent the roller turning from the weight of the curtain by slitting the roller longitudinally near the end and entering said end within a ring-bracket that is slightly smaller than the roller, so that the said roller will be contracted as forced into the ring, the slitting allowing of this and the spring of the wood causing friction.

In the drawings, *a a* represent portions of the window-casing. *b* is the wooden roller, the end of which is slitted at *c c*, to form springing ends that are compressed into the ring-bracket *d* secured upon the casing; and said device affords a friction to prevent the weight of the curtain causing the roller to turn.

The cord-ring *e* is made with a grooved periphery for an endless cord, *f*, and the hole through this cord-ring is of a size to fit the roller *b*, and teeth *i i*, projecting inward, enter the sides of the wooden roller as that is forced through the cord-ring, and said teeth hold the cord-ring securely in place.

h is a semicircular shoe or bracket receiving the end of the curtain-roller *b* near the cord-ring *e*.

What I claim, and desire to secure by Letters Patent, is—

1. The cord-ring *e*, formed with a groove around its periphery for an endless cord, an opening through it for the curtain-roller to pass entirely through to its bearing, and with teeth to penetrate said roller, as and for the purposes set forth.

2. The combination of the semicircular shoe or bracket *h* with the cord-ring *e* and roller *b*, as and for the purposes set forth.

3. The friction-spring for the curtain-roller, formed by slitting the ends of the said roller and introducing it within a ring or bracket, as set forth.

In witness whereof I have hereunto set my signature this 4th day of May, A. D. 1866.

J. B. BAILEY.
